W. H. MORGAN,
RAILROAD TRACK CONSTRUCTION,
APPLICATION FILED JAN. 31, 1913.

1,072,761.

Patented Sept. 9, 1913.

UNITED STATES PATENT OFFICE.

WILLIAM HENRY MORGAN, OF ALLIANCE, OHIO.

RAILROAD-TRACK CONSTRUCTION.

1,072,761.

Specification of Letters Patent. Patented Sept. 9, 1913.

Application filed January 31, 1913. Serial No. 745,396.

To all whom it may concern:

Be it known that I, WILLIAM H. MORGAN, of Alliance, in the county of Stark and State of Ohio, have invented certain new and useful Improvements in Railroad-Track Construction; and I do hereby declare the following to be a full, clear, and exact description of the invention, such as will enable others skilled in the art to which it appertains to make and use the same.

My invention relates to railroad track construction, and is an improvement on the invention disclosed in Patent No. 1,026,106 granted to W. V. Hartzell and myself May 14th, 1912. In the above patent, the rails are supported on alternately arranged Z shape and straight metal ties, the rails resting on the parallel member of the Z shaped tie and crossing the straight ties at right angles, there being no connection between the two sets of ties other than the rails which are secured to both.

The object of this invention is to provide means whereby the straight ties help support the Z-shaped ties, and also the joint in the rails.

A further object is to connect all the ties in series so as to stiffen the whole structure and prevent any turning movement of the ties.

In the accompanying drawings, Figure 1 is a view of a section of a track showing the connection between the ties and also showing one rail in place; Fig. 2 is a view in plan; Fig. 3 a view in side elevation and Fig. 4 a view in end elevation of one of the Z-shaped ties; Fig. 5 is a view of one of the straight ties and Fig. 6 is a view in section longitudinally through one of the cushion plates, rail chair and rail supporting member of a Z-shaped tie.

1 represents the Z-shaped ties and 2 the straight ties, both made of metal and substantially I-shape in cross section, with their base flanges wider than their top flanges, and bent downwardly at opposite side of the web or body of the tie into inverted V form. With this shape of base flange, a load on the ties, causes the ballast to pack under them and hold them solidly immediately under the rails, and thus prevent center binding of the ties.

The parallel or rail supporting members of the Z-shaped ties are provided with one or more cushion plates or seats 3, spot, or

line welded, or riveted or otherwise secured to the top flange of the rail supporting members of the tie. The ends of these plates are bent upwardly and then horizontally to form seats or supports for the 60 chairs or gage plates 4, and the extreme ends are turned downwardly to form stops, as clearly shown in Fig. 4, for the spring clamps 5 which lock the parts together. The long axes of these cushion plates 3 extend in the direction of the length of the rail supporting members of the ties 1, and are such height that when the chair or gage plate 4 is seated thereon, the depending flanges 6 of the latter, will terminate above 70 the top of the tie, and act as a cushion or yielding support for the rail. The straight ties 2 are also provided with the cushion plates or seats 3, which extend transversely of said ties as shown in Fig. 5, and are of 75 course in line with the cushion seats on the parallel rail supporting members of the Z-shaped ties.

The chairs or gage plates 4 are substantially as shown in my Patent 1,026,108 80 granted May 14th, 1912 except that they are longer and each comprises a body having depending flanges 6 and upwardly projecting flanges 7 at its side edges.

The ties 1 and 2 are alternately arranged 85 so that one straight tie is intermediate two Z-shaped ties, and they are so placed as to leave but little clearance between the ties.

Each chair or gage plate 4 is of a length sufficient to extend approximately the length 90 of the rail supporting members of the ties 1, and beyond the free ends of said members, so as to engage and rest on a seat 3 on the tie 2 as shown in Fig. 1, so that each chair or gage plate is supported on one rail 95 supporting member of tie 1, and also on the straight tie 2 adjacent the free end of said rail supporting member. It will therefore be seen that one chair rests at one end on the cushion seat secured to one rail supporting member of a Z-shaped tie, and at its other end on the cushion seat on the straight tie adjacent the free end of said member, and the other chair rests on the cushion seats on the other arm of said Z-shaped tie, and on the cushion seat on the straight tie adjacent said free end, so that each Z-shaped tie is connected to the straight tie at each side thereof, and each straight tie is connected to the two adjacent Z-shaped 110

ties. The depending flanges 6 of each chair or gage plate 4 overhang and bear against the side edges of the raised seats of the cushion plates 3 and absolutely prevent any lateral or spreading movement of the chairs, and consequently of the rails seated on the chairs. The rail rests on the chair between the upwardly projecting flanges 7 of the latter, the inner walls of which flanges are different distances from the center of the chair, so that by reversing the position of the chair, end for end, the rail 8, the base flange of which rests between is sustained laterally by said flanges 7, may be adjusted toward its companion rail to compensate for wear.

The ties, and cushion seats are designed to sustain any size rail. The chairs are grooved on the underside to fit the cushion seats, while the groove in the upper side of the chair is adapted for a rail of a particular size, hence when it is desired to change from a lighter to a heavier rail, or vice versa, it is only necessary to change the chairs.

The parts above described are locked together by the spring clamps 5, each of which is substantially U-shape. The upper end of each clamp bears against the top flange 30 of the chairs, and overhangs the base flange of the rail, without actual contact therewith but sufficiently close to hold the rail in position, while the lower end of the clamp rests in rear of a rib 10 on the armor plate 11 which is supported against the underside of the cushion seat 3, as shown in Fig. 6.

The clamps 5 above referred to, are preferably made of hard tough and finely grained steel or alloy, of a size sufficient to hold the chairs or gage plates on their cushion seats, and also prevent any undue or tilting movement of the rail on its plates. These clamps may be inserted and driven on endwise in the direction of the length 45 of the chairs, or they may be sprung on over the side edge of the base flange of the rail.

While in some instances it may be preferred to have the upper members of the clamps bear directly on the base flange of the rail, I have in the present instance shown a slight clearance between the top of the base flange of the rail and the free end of the clamp, so as to permit the rail to have a slight vertical movement under 50 a rolling load without disturbing the tie in the ballast. The rails are therefore preferably loosely seated on the chairs or gage plates, but as the resultant of the wheel pressure always falls within the bases of the rails, the only pressure to which the rail is subjected, other than downward, in an outward one which is taken care of by the side flanges on the chairs or gage plates, hence there is theoretically, no tendency for the rails to tip,

but as the ends of the clamps overhang the base flanges of the rails, and are only removed therefrom a limited distance, tipping of the rails, to anything like a dangerous extent would be absolutely prevented 70 by the clamps.

With this construction, the straight ties help support the rail supporting members of the Z-shaped ties, and as all the ties are connected in series, the whole structure is stiffened and the possibility of any change in relative position of any one of the ties is prevented. Again with this arrangement the joints of the rails will be supported by two ties, instead of by one as might be the case where the ties are not connected.

It is evident that many slight changes might be resorted to in the relative arrangement of parts shown and described without departing from the spirit and scope of my invention. Hence I would have it understood that I do not wish to confine myself to the exact construction and arrangement of parts shown and described, but,

Having fully described my invention 90 what I claim as new and desire to secure by Letters-Patent, is:—

1. The combination of alternately arranged Z-shape and straight metal ties, rail supporting chairs extending from one tie to the other, the said chairs having downwardly projecting flanges to overhang parts of two ties and upwardly projecting flanges to engage the side edges of the base flanges of the rail, and means for securing the 100 chairs and rails to the ties.

2. The combination of alternately arranged Z-shape and straight metal ties each having seats projecting above the top faces of the ties, rail supporting chairs extending from one tie to the other and resting on seats on both ties, the said chairs having downwardly projecting flanges to overhang the seats on the ties, and upwardly projecting flanges to engage the side edges of the 110 base flanges of the rails, and means for securing the parts together.

3. The combination of alternately arranged Z-shape and straight metal ties, rail supporting chairs extending from one tie to the other, the said chairs having downwardly projecting flanges to overhang parts of two ties and upwardly projecting flanges to engage the side edges of the base flanges of the rails, and spring clamps for securing 120 the chairs and rails to the ties.

4. The combination of alternately arranged Z-shape and straight metal ties each having seats projecting above the top faces of the ties, rail supporting chairs extending from one tie to the other and resting on seats on both ties, the said chairs having downwardly projecting flanges to overhang the seats on the ties, and upwardly projecting flanges to engage the side edges of the 130

base flanges of the rails, and flexible means for fastening the chairs and rails to said seats.

5. The combination of alternately arranged Z-shape and straight metal ties, cushion seats secured to the top surfaces of both sets of ties, rail supporting chairs each resting on the seats on one rail supporting member of a Z-shape tie and on the seat 10 on the next adjacent straight tie, the said chair having downwardly projecting flanges to engage the sides of the seats, and upwardly projecting flanges to engage the side edges of the base flanges of the rails, 15 and means for securing the chairs and rails to the seats.

6. The combination of alternately arranged Z-shape and straight metal ties,

cushion seats secured to the top surfaces of both sets of ties, rail supporting chairs each 20 resting on the seats on one rail supporting member of a Z-shape tie and on the seat on the next adjacent straight tie, the said chair having downwardly projecting flanges to engage the sides of the seats, and upwardly 25 projecting flanges to engage the side edges of the base flanges of the rails, and spring clamps for securing the chairs and rails to the cushion seats.

In testimony whereof, I have signed this 30 specification in the presence of two subscribing witnesses.

WILLIAM HENRY MORGAN.
